UNITED STATES PATENT OFFICE

2,196,558

RAW STOCK DYEING APPARATUS

Stonewall W. Jackson, Columbus, Ga., assignor
to Morton Machine Works, Columbus, Ga.

Application January 17, 1939, Serial No. 251,438

3 Claims. (Cl. 68—187)

The invention relates to dyeing apparatus of the general type having a removable vat cover and a perforated plate below said cover to rest on stock being dyed, to prevent channeling.

More specifically, the invention relates to an apparatus similar to that disclosed in the F. M. Morton, U. S. Patent No. 1,737,940, of December 3, 1929, in which the perforated plate is so connected with the cover that said cover can move further down to closed position after the plate initially rests on the stock, the plate can vertically move with any vertical movements of the stock during dyeing, and removal of the cover will also effect removal of the plate.

The principal object of the invention is to provide an improved sliding connection between the plate and the cover having no parts projecting downwardly from said plate with danger of catching in the stock.

Another object is to provide an exceptionally simple and inexpensive construction, yet one which will be effective and durable.

With the foregoing in view, the invention resides in the novel subject matter hereinafter described and claimed, description being accomplished by reference to the accompanying drawing.

Figure 1 is a top plan view of a dye vat and its cover, equipped with the invention.

Figure 2 is a vertical sectional view on line 2—2 of Fig. 1.

Figure 3 is a disassembled sectional view showing the improved connecting means.

A preferred construction has been illustrated and will be rather specifically described, with the understanding, however, that within the scope of the invention as claimed, variations may be made.

A cover 5 is shown for a vat 6, and clamps 7 have been illustrated for securing said cover in closed position. The cover 5 in the present disclosure is provided with an inlet 8 for the dye liquor, and an outlet 9 is provided from the bottom of the vat beneath a perforated false bottom 10.

A perforated plate 11 is provided to rest on the raw stock, to prevent channeling in the usual way, and novel connecting means is provided between this plate 11 and the cover 5, said connecting means preferably consisting of a plurality of units 12 all constructed in the same manner. Hence, a description of one unit will suffice for all.

A vertical hollow cylinder 13 extends through an opening 14 in the cover 5 and is provided

with a continuous lateral flange 15 secured upon said cover by cap screws or the like 16, the upper end of said cylinder being closed by a suitable plate 17 which may be secured in place by screws or the like 18. The lower end wall 19 of the cylinder 13 is formed with an opening 20 through which a vertical stem 21 passes slidably, said stem being rigidly secured to the perforated plate 11 and having a head 22 slidable in the cylinder 13, said head projecting laterally in all directions from said stem. In securing the stem 21 to the plate 11, I provide the lower end of said stem with a reduced portion 23, pass this portion through an opening 24 in the plate, and thread a nut 25 on said reduced portion in contact with the lower side of said plate. The entire stem can thus move vertically with the plate 11, downward movement of this plate being limited by the head 22 striking the lower end wall 19 of the cylinder 13, whereas upward movement 20 of said plate is limited by striking of said end wall against said plate.

By providing the novel construction shown and described, the objects of the invention are readily attained, particular attention being invited to the fact that the novel connecting means between the cover and the plate possesses no downwardly projecting portions to become entangled in the stock.

As excellent results may be obtained from the details disclosed, they are preferably followed. However, within the scope of the invention as claimed, variations may, of course, be made.

I claim:

1. In a dyeing apparatus having a vat cover and a perforated plate under said cover to rest on stock being dyed; connecting means between said plate and cover comprising a hollow vertical cylinder secured to said cover and having upper and lower end walls, said lower end wall being formed with an opening, and a stem secured to and projecting upwardly from said plate, said stem passing slidably through said opening and having a laterally projecting portion slidable in said cylinder, said laterally projecting portion being disposed in position to rest upon said lower end wall of said cylinder when said perforated plate occupies its lowest position with respect to said vat cover.

2. In a dyeing apparatus having a vat cover and a perforated plate under said cover to rest on the stock being dyed; connecting means between said plate and cover comprising a hollow vertical cylinder extending through an opening in said cover and having a lateral flange se-

cured to the latter, said cylinder having upper and lower end walls, the latter of which is formed with an opening, and a stem secured to and projecting upwardly from said plate, said 5 stem passing slidably through said opening and having a laterally projecting portion slidable in said cylinder, said laterally projecting portion being disposed in position to rest upon said lower end wall of said cylinder when said perforated 10 plate occupies its lowest position with respect to said vat cover.

3. In a dyeing apparatus having a vat cover

member and a perforated plate member under said cover member to rest on stock being dyed; two elongated slidably telescoped connecting members secured one to said cover member and the other to said plate member to allow vertical movement of the latter with respect to the former, and coacting means on said telescoped members to abut and limit the downward movement of said plate member with respect to said cover member.

10
